US00D826932S

(12) **United States Design Patent** (10) **Patent No.:** **US D826,932 S**
(45) **Date of Patent:** **** Aug. 28, 2018**

(54) **WEARABLE DEVICE**

(71) Applicant: **SAMSUNG ELECTRONICS CO., LTD.**, Suwon-si, Gyeonggi-do (KR)

(72) Inventors: **Ridhi Chugh**, Haryana (IN); **Siddhartha Sen Choudhary**, Uttar Pradesh (IN); **Vivek Kumar Mishra**, Uttar Pradesh (IN); **Agarwal Pankaj**, Suwon (KR)

(73) Assignee: **SAMSUNG ELECTRONICS CO., LTD.**, Gyeonggi-Do (KR)

(**) Term: **15 Years**

(21) Appl. No.: **29/566,468**

(22) Filed: **May 31, 2016**

(30) **Foreign Application Priority Data**

Dec. 4, 2015 (KR) 30-2015-0061876

(51) **LOC (11) Cl.** **14-02**

(52) **U.S. Cl.**

USPC **D14/344**; D10/26

(57) **CLAIM**

The ornamental design for a wearable device, as shown and described.

DESCRIPTION

FIG. 1 is a front perspective view of a wearable device showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof, as shown in a user environment.

The evenly spaced broken lines and the dot-dash broken lines in FIG. 8 illustrate a user environment; the remaining broken lines depict portions of the wearable device. The broken lines form no part of the claimed design.

1 Claim, 8 Drawing Sheets
